LEWIS M. McBRIDE, OF DENVER, COLORADO, ASSIGNOR TO THE McBRIDE-FRAZIER ARC LAMP COMPANY, OF DENVER, COLORADO, A CORPORATION OF COLORADO.

ELECTRIC-ARC LAMP.

1,039,162.

Specification of Letters Patent. Patented Sept. 24, 1912.

Application filed October 18, 1909. Serial No. 523,175.

To all whom it may concern:

Be it known that I, LEWIS M. McBRIDE, a citizen of the United States of America, residing in the city and county of Denver 5 and State of Colorado, have invented a new and useful Electric-Arc Lamp, of which the following is a specification.

This invention relates to improvements in electric arc lamps, and particularly to a 10 style of lamp adapted to be used in connection with headlights, stereopticons, moving picture machines and search-lights.

The object of the invention is: first, to provide a lamp in which the usual flickering of the light, due to the feeding of the electrodes, is prevented; second, to provide a lamp in which the arc is maintained in a predetermined fixed position, such as the focal point of a reflector used in conjunction with said lamp; and, third, to provide in connection with said lamp means for controlling and directing the arc along the axis toward the vertex of the said reflector. These objects are accomplished by the mechanism illustrated in the accompanying drawings, in which:

Figure 1 is a view in elevation of the improved lamp arranged in connection with a parabolic reflector, the rear end of which is 30 cut off on the line 1—1 of Fig. 2, for clearer illustration. Fig. 2 is a central, vertical, longitudinal, sectional view through the lamp, reflector and supporting bracket therefor. Fig. 3 is a front view showing the lamp 35 used in connection with an ordinary headlight casing, provided with a housing for receiving the upper ends of the electrode tubes and parts of the lamp mechanism. Fig. 4 is a plan view of Fig. 3, showing more 40 clearly the hinged doors, which normally cover the openings through which the electrodes are passed into the holding tubes. Fig. 5 is a plan view of a portion of the lamp-supporting bracket; and Fig. 6 is a 45 diagrammatic view illustrating the lamp circuit.

Referring to the accompanying drawings: The numeral 1 indicates a headlight casing having the usual glass-front door 2 hinged 50 thereto. Within the casing is placed a reflector 3, which is secured upon a bracket 4, which is adapted to be slid into the end of the casing. As illustrated in Fig. 2, the bracket 4 comprises a horizontal base portion 5, which is adapted to rest in guides

(not shown) within the casing, a vertical portion 6, to which the end of the reflector is secured, and a platform 7, to which the parts comprising the improved lamp are secured, as will now be described.

The platform 7 is provided at opposite ends with elongated apertures 8, and at the outside ends of the apertures are secured supports A and B respectively, each of which consists of a plate 9, having parallel 60 ears 10, which lie on opposite sides of the aperture 8, and between each pair of ears is pivotally secured, in any suitable manner, an electrode holding and feeding tube 11, which tubes extend through apertures 12, 65 in the reflector and converge to a point on a line with the vertex of the said reflector. The plates 9 are insulated from the platform 7.

The feed tubes 11 extend a suitable distance above their supports, and the upper portions enter a housing 13, which is formed on the top of the casing 1. The top of the housing is formed with openings 14, in line with the adjacent ends of the tubes, through 70 which the electrodes 15 are passed into the said tubes, and these openings are normally closed by hinged lids 16. The tubes are provided with stops 17, at their lower ends, which consist of pieces of a highly refractory substance, preferably carborundum, which fit in holders 18, formed on the end of the tubes. These holders are arranged at a slight angle to the tubes, so that their axes intersect the axes of the tubes a slight distance below the ends of the same; thus, when the stops 17 are inserted in the holders, as 75 clearly shown in Fig. 1, they extend across the paths of the electrodes, which extend a slight distance beyond the lower ends of 80 the tubes, and prevent their downward movement beyond a predetermined point.

Upon the platform 7, centrally between the tube supporters, is secured a solenoid 19 of the usual type, and in the lower end of the axial opening therein is secured an iron pole 20, which extends down through the reflector. The portion of the pole 20 lying within the reflector is flattened to form a blade which lies between the electrode tubes and extends 100 to within a short distance of their point of convergence. This pole forms a blow magnet for a purpose to be presently explained, and by flattening the same it not only is prevented from casting a shadow, but may be 105 110

extended to within a slight distance of the converging point of the tubes, as above stated.

An iron plunger 21 extends into the upper 5 end of the solenoid and terminates a suitable distance from the upper end of the pole 20. The opposite end of the armature is secured in the bottom of a movable dash pot cylinder 22, within which a piston 23 is sup- 10 ported upon an adjustable threaded rod 24, which extends loosely through an aperture in the horizontal arm 25 of an upright bracket 26, which is secured at its lower end upon the top of the solenoid. A thumb nut 15 27 is threaded to the upper end of the rod 24 and bears upon the arm 25, and by turning the said nut the rod and the piston 23 are adjusted vertically relatively to the dash pot. A cross bar 28 is secured upon the 20 upper portion of the rod 24 by nuts 29, and this bar is connected by a pair of helical springs 29^A, with ears 30, which project from opposite sides of the dash pot, and these springs normally hold the dash pot in 25 a predetermined position relatively to its piston.

A cross head 31 of non-conducting material, preferably fiber, is suitably secured upon the armature 21, between the dash pot 30 and the solenoid, and a pair of toggle arms 32 are pivotally secured at their lower ends to opposite sides of this block, adjacent to its ends, and the upper ends of the arms are pivotally secured between ears 33, which 35 form the terminal ends of bands 34, which are secured upon the electrode tubes; thus when the plunger descends in the solenoid the toggle arms draw upon the feed tubes, which are rocked on their pivots to separate 40 the lower ends of the electrodes. The feed tube supports A and B are provided with binding screws 35 and 36 respectively, and a wire 37 connects the screw 35 with one end of the solenoid winding, while a wire 45 38 extends from the screw 36 of the support B to a battery 39, or other source of power. A wire 40 extends from the opposite end of the solenoid winding to a resistance 41, and from the resistance a wire 42 50 extends to the source of power.

When the electric circuit through the feed tubes and solenoid is open the lower ends of the electrodes contact, but when the circuit is closed the plunger under the influence of the current in the solenoid winding 55 is drawn into the solenoid and the cross head 31 is thereby moved downward, drawing upon the toggle arms 32, which rock the feed tubes on their pivots, and separate the lower ends of the electrodes, thus forming 60 an arc, the space between the ends of the electrodes being determined by the

amount of resistance offered by the springs 29^A to the action of the solenoid.

It is a well known principle in magnetic phenomena that a magnetic flux will produce a pressure on an arc, in general proportional to the strength of arc, flux, and relative directions of the two. The solenoid is so wired and its axis so positioned, 65 that, for a given direction of current in the arc, and hence in the solenoid, since its windings are in series with the carbons, the magnetic flux direction will be such as to exert a pressure upon the arc and approximately at right angles to it, and in such direction as to push the arc to the lower extremity of the carbons. When the current direction in the arc is reversed, of necessity, the current in the coil is likewise reversed, 70 and hence the polarity of the magnetic field is reversed. Thus the direction of the side thrust of the flux on the arc is constant, keeping the arc in one position, viz., the lower extremity of the carbons. Under the 75 influence of the magnetic flux of the blow magnet 20 the arc is maintained more nearly in the focal axis of the reflector, and this in conjunction with the uniform feeding of the electrodes not only eliminates flickering 80 but prevents the arc from burning out of focus, thus giving much clearer and steadier light than would be possible when these conditions are lacking.

The feed tubes are preferably made of 85 brass or copper, and are nickel-plated in order to diffuse the light and prevent shadows.

The dash pot prevents sudden movement 90 of the armature, due to the action of the current in the solenoid.

Having described my invention, what I claim as new and desire to secure by Letters Patent is:

An electric arc-lamp having an electrode 105 actuating solenoid, a plunger in said solenoid, a cylinder secured to the upper end of said plunger, a piston within said cylinder, a threaded rod secured to said piston, a support for said threaded rod, a cross-bar 110 adjustably secured on said threaded rod having springs attached to its outer ends, and bands encircling the cylinder having projecting ears secured to the other ends of said springs, thereby providing means for 115 keeping said cylinder normally in a fixed position.

In testimony whereof I affix my signature in presence of two witnesses.

LEWIS M. McBRIDE.
